UNITED STATES PATENT OFFICE

HANS FRANZEN, OF MANNHEIM, GERMANY, ASSIGNOR TO I. G. FARBENINDUSTRIE AKTIENGESELLSCHAFT, OF FRANKFORT-ON-THE-MAIN, GERMANY, A CORPORATION OF GERMANY

DISTILLATION

Application filed January 22, 1929, Serial No. 334,183, and in Germany February 8, 1928.

It has been proposed to expel volatile substances from fats or oils, such as mineral oil, brown coal tar oil, coal tar oil and the like, by introducing liquids of organic nature of a low boiling point, such as benzine, alcohols, alkyl halides and the like, or water, into the said oils, the latter being heated to temperatures above the boiling points of the said liquids of low boiling point. When coming into contact with the hot oils or other substances being treated, the said liquids of low boiling point become strongly superheated and vapors thereof are explosively generated, within the mass of the material in the still, which vapors become intimately intermingled with the liquid under treatment, whereby as the result of their high force of expansion, a thorough distillation is obtained. It has also been proposed, for the purpose of introducing the liquid in a finely divided state, to employ its own vapor, or some other gas, as carrier. One defect of this method of working consists in the fact that it entails a rather considerable expenditure of energy for heating and transporting the carrier, a circumstance which has an adverse influence on the economy of the process.

I have now found that the introduction of a liquid into another liquid which is heated to a temperature above the boiling point of the former, can be effected, in a simple and reliable manner, even without the use of carriers, by allowing only a portion of the admitted current of liquid to flow directly into the liquid under treatment, the remainder of the liquid current being employed as a heat insulating medium between the liquid under treatment and the liquid to be introduced, in order to prevent excessive heating and consequent premature vaporization of the latter. In order to prevent such premature vaporization, the liquid may be introduced under elevated pressure, the employment of which, owing to its action in raising the boiling point of the liquid, also affords the possibility of enabling the liquid introduced to be passed at a slow rate through the apparatus, in order that, by utilizing the reserve of heat contained in the liquid surrounding the

apparatus, the liquid introduced can be heated nearly to its boiling point within the apparatus itself, a circumstance which may be advantageous in some cases, as for example for thermotechnical reasons.

The apparatus illustrated in the accompanying diagrammatic drawing has been found particularly suitable for carrying out the process. A pipe C, provided with a lateral intake tube A, fits tightly at its upper end into a wider pipe D, provided with a lateral delivery tube B, the lower end of the pipe D being closed by a lid having a comparatively narrow central outlet orifice F. The outflow through the orifice F is regulated by a valve 55 rod E passing through a stuffing box at the upper end of the pipe C. This device is inserted into a shell G. It has been found that this apparatus can be successfully employed, inter alia, for the separation of volatile substances from heavy or non-volatile substances by means of superheated steam.

The following example will further illustrate the nature of the said invention which however is not limited thereto.

Example

Peanut oil containing 5 per cent of free fatty acid is heated to 280° centigrade in a vacuum apparatus G in which the device 80 hereinbefore described is inserted so that its orifice is at the lowest possible point. The valve E being closed, a current of water, under a pressure of 8 atmospheres, is passed through the device at such a gradual rate 85 that the effluent water has a temperature of for example about 175° centigrade. Under these conditions, no vaporization of the water can occur in the device. The valve E being carefully opened, water passes from the inner pipe into the peanut oil, where it vaporizes in an explosive manner, and the fatty acid is driven off by the resulting highly superheated steam. Within a short time the peanut oil will be practically free from fatty 95 acid.

The expenditure of energy is substantially less than if the water were introduced with the assistance of gaseous carriers; and the amount of steam to be condensed is also very 100

considerably smaller than if superheated steam, for example, were employed as the carrier.

What I claim is:—

5. 1. An apparatus suitable for the distillation of organic liquids which comprises a still, two concentrically arranged pipes in said still, both being closed at one end, and provided at said closed ends with means for admitting liquid to the inner of said pipes and withdrawing it from the outer pipe, the outer pipe being provided at the opposite end with a lid containing an aperture of a diameter considerably smaller than that of the inner pipe.
10. 2. An apparatus suitable for the distillation of organic liquids which comprises a still, two concentrically arranged pipes in said still, both being closed at one end, and provided at said closed ends with means for admitting liquid to the inner of said pipes and withdrawing it from the outer pipe, the outer pipe being provided at the opposite end with a lid containing an aperture of a diameter considerably smaller than that of the inner pipe, and means for controlling the area of said aperture.
15. 3. An apparatus suitable for the distillation of organic liquids which comprises a still, two concentrically arranged pipes in said still, both being closed at one end, and provided at said closed ends with means for admitting liquid to the inner of said pipes and withdrawing it from the outer pipe, the outer pipe being provided at the opposite end with a lid containing an aperture of a diameter considerably smaller than that of the inner pipe, and a movable stem passing through said inner pipe and being so arranged as to control the area of said aperture.
20. 4. In a process of distillation by the introduction into an organic liquid to be distilled of another liquid inert to said organic liquid, and having a boiling point below that of said organic liquid while heating said organic liquid to a temperature above the boiling point of said inert liquid, the step of dividing said inert liquid into a portion introduced into the organic liquid to be distilled and another portion insulating the former during its introduction into the said organic liquid to be distilled.
25. 5. In a process of removing free fatty acids from a vegetable oil containing the same by the introduction into the oil of another liquid, inert to said oil and having a boiling point below that of said oil, while heating said oil to a temperature above the boiling point of the said inert liquid, the step of dividing said inert liquid into a portion introduced into the oil to be distilled, and another portion insulating the former portion from the oil during its introduction into the said oil.
30. 6. The process for distilling organic liquids comprising confining a body of a

liquid of a lower boiling point than the liquid to be distilled in an enclosed space in a heated body of said latter liquid, forming said liquid body of lower boiling point into two concentric layers whereby the outer layer insulates said inner layer and carefully injecting liquid from said inner layer into said heated liquid body.

7. The process as defined in claim 8 where-in the liquid to be distilled is an oil and the liquid of lower boiling point is water.

8. The process for distilling fatty acids from peanut oil comprising confining a body of water under a pressure of about 8 atmospheres in an enclosed space in a body of said peanut oil heated to a temperature of about 280° C. and under a reduced pressure, forming said body of water into two concentric layers whereby the outer layer insulates said inner layer and carefully injecting water from said inner layer into said heated body of peanut oil.

In testimony whereof I have hereunto set my hand.
